UNITED STATES PATENT OFFICE.

ERNEST F. MECHLIN, OF WASHINGTON, DISTRICT OF COLUMBIA, ASSIGNOR TO THE
T. H. SYMINGTON COMPANY, OF BALTIMORE, MARYLAND, A CORPORATION OF
MAINE.

DRAFT-RIGGING.

1,250,481.

Specification of Letters Patent.

Patented Dec. 18, 1917.

Application filed May 11, 1917. Serial No. 167,947.

To all whom it may concern:

Be it known that I, ERNEST F. MECHLIN, a citizen of the United States, residing at Washington, District of Columbia, have invented certain new and useful Improvements in Draft-Rigging; and I do hereby declare the following to be a full, clear, and exact description of the invention, such as will enable others skilled in the art to which it appertains to make and use the same.

The invention disclosed in this application (which is a substitute for an earlier application filed by me November 12, 1915, Serial No. 61,135) relates to draft rigging for railway cars and more particularly to that class of draft riggings in which one or more of the operative elements thereof are connected to the other elements by means of a removable key or keys.

In this form of draft rigging it has been the usual and common practice to retain the key or keys in position by cotters located near the ends of the key, the said cotters being usually arranged adjacent a stationary part of the car or draft rigging, and since all the keys have movement the cotters are brought into contact with these stationary parts and are apt to be worn.

The main feature of the invention generally stated comprises, in combination with a draft rigging of the kind described, means located intermediate the car sills to retain the key or keys in proper assembled position.

There are other features of the invention as will appear from a more detailed description thereof taken in connection with the accompanying drawing chosen for the purpose of illustrating one embodiment of the invention wherein

Figure 1 is a top plan view;

Fig. 2 is a section on line 2—2 of Fig. 1;
Fig. 3 is a detailed section view on a slightly larger scale;

Fig. 4 is a section on line 4—4 of Fig. 3; and

Fig. 5 is a view similar to Fig. 3 showing, however, a slightly modified form of locking piece.

In the drawing, 1 designates the center or draft-sills of a car to which the draft-rigging 2 is connected, 3 is the coupler, 4 and 5 are the followers, 6 the spring device interposed between the followers 4 and 5. The combined tie and brace 7 is located in rear

of the rear follower 5 and preferably spaced therefrom as shown. The numeral 8 designates the means to operatively connect the coupler 3 to the rear follower which means may consist of a pair of rearwardly extending links or bars which are slotted to receive the keys 9 that also pass, respectively, through slots 10 in the followers and coupler as well as through the sills.

To retain each key in its assembled position a fastening means is provided. Said means may be and preferably is in the form of a bar 11 and, in the special form of draft-rigging illustrated in the drawing is adapted to be inserted from below in a vertical direction into openings 12, specially formed in the follower blocks 4 and 5 and accustomarily provided in the coupler to receive one of the standard coupler rivets. It will be noted from an inspection of the drawing that the openings 12 are so located and arranged with reference to the keys that each opening intersects a portion of the keys which pass through the followers and draw-bar, and at this point the several keys are each provided with a notch or opening 14.

The bars 11 may and preferably are provided for a portion of their length with substantially flat sides 13, the said sides, as shown in Fig. 4, being adapted to closely fit correspondingly shaped sides of the openings 14, to thereby hold the said bars 11 from rotation with respect to the said keys.

Each bar 11 is for convenience formed with a recess or slot 15 adapted to receive therein a locking piece 17. The end of the said slot or recess is formed by an angularly extending wall or shoulder 16, as shown.

The locking piece 17 is connected to the bar 11 in any convenient manner, as for example by means of a split key or cotted 20, the said cotted being adapted to pass through registering openings 21 formed in the bar 11 and the locking piece 17. Each locking piece is preferably provided with a head 18 which may be formed with an inclined portion 19 adapted to co-operate with the inclined portion 16 of the bar 11. A lip 20 is conveniently formed on the head portion 18, said lip being adapted when the bar 11 is in proper assembled position to overlie a portion of the key 9 and thus serve to retain the bar 11 in position.

The mode of assembling the form of de-

vice above described is as follows: After one of the keys has been put into proper position within either a follower or the draw-bar, with the slot thereof in register with the opening 12, the bar 11 is inserted into the opening 12 with the inclined portion thereof above the upper surface of the key. The locking piece is then inserted and owing to the co-operating inclines on the bar and locking piece the head of the latter member will move outwardly with respect to the bar and into locking position with the lip 20 thereof resting upon the upper surface of the key 9. When and only when the locking piece occupies this position with reference to the bar, are the openings 21 in register and to retain the locking piece in position with reference to the bar the cotter 20^a is inserted. The said cotter serving to prevent relative movement between the locking piece and bar and between the bar and the key.

In the form of the device illustrated in Fig. 5 the bar 11^a is provided with a slotted or recessed portion 15^a in which portion the locking piece 17^a is adapted to be pivotally connected by means of the pivot pin 16^a. A head 18^a is provided at one end of the said locking piece and formed thereon is a lip 19^a adapted to overlie the key 9 when the parts are in assembled and locked position. Adjacent the pivot 16^a the locking piece 17^a is preferably provided with an angularly extending portion 20^b having a slot or opening 20^c formed therein, one edge of the said opening, when the locking piece is in locking position, being tangential to the bar. A cotter pin 21^a or other convenient form of fastening means is adapted to pass through the opening 20^c to maintain the locking piece in locked position.

It will be evident from the foregoing description that I have devised a strong and simple fastening means which will maintain the keys in proper assembled position and which while easy to remove and insert, maintains, when in position, the keys firmly in place. It is to be noted that since the bars 11 have no movement with respect to either 50 of the parts with which they engage, all wear on the fastening device is entirely eliminated.

Having now described one embodiment of the invention, what I claim and desire to secure by Letters Patent is:

1. In combination with the draft sills of a car, a draft rigging mounted therebetween and having a transversely extending removable key forming one of the component parts 60 of the draft rigging, a key retaining device insertible from below and located intermediate the sills and adapted to engage the said key, and means movable laterally with respect to said retaining device into engagement with an upper face of a part of said

draft rigging to support said device in operative position.

2. In a draft rigging, the combination with the coupler, of a spring device, means for operatively connecting said coupler and 70 spring device, said means involving a key and a downwardly removable means for retaining said key in assembled position, said retaining means involving a bar engaging said key and a locking device for maintaining said bar in assembled position, said locking device being movable laterally with respect to said bar when being assembled or disassembled and being removable with said bar.

3. In combination with a draft rigging, a removable key passing through one of the movable parts thereof, a retaining device for said key, adapted to maintain said key in operative position, and a locking and supporting means for said device, said means being adapted to extend at an angle to said device and being movable laterally thereof to permit the downward removal of said retaining device and said locking means.

4. In combination with a draft rigging, a transversely extending key adapted to pass through one of the movable elements of said draft rigging, means insertible from below and extending at an angle to said key to retain said key in proper assembled position, said means being provided with locking means said last named means being movable laterally with respect to said first named means into locking or unlocking positions.

5. In combination with a draft rigging, a transversely extending key mounted in one of the movable elements of said draft rigging and a bar insertible from below into said movable element to retain the key in proper assembled position and means extending within said movable element for maintaining said bar in retaining position.

6. In combination with a draft rigging, a transversely extending key mounted in one 110 of the movable elements of said draft rigging and a bar adapted to be inserted into said movable element from below to hold the key in proper assembled position and means movable laterally with respect to said bar 115 and extending within said movable element and adapted to prevent vertical movement of said bar.

7. In combination with a draft rigging, a transversely removable key adapted to extend through one of the movable elements of said draft rigging, and a retaining device for said key comprising a plurality of parts having a wedged engagement therebetween.

8. In combination with a draft rigging, a 125 transversely removable key adapted to extend through one of the movable elements of said draft rigging, and a bar insertible from below into the element having the said key, said bar being adapted to retain the 130

key in proper assembled position, and laterally movable means projecting laterally beyond said bar within said movable element and adapted to retain the bar in proper position.

9. In a draft rigging employing transversely extending keys as coupler connecting means, bars located intermediate the center sills of the car, said bars each being adapted to engage a key to retain the same in operative position, each of said bars being

provided with a member which is laterally movable with respect to said bar, said member being adapted to engage the key to support the bar in assembled position, and additional means also extending laterally with respect to said bar and being adapted to engage a relatively thick portion of the draft rigging to hold the bar from rising.

In testimony whereof I affix my signature. 20

ERNEST F. MECHLIN.
